[57] CLAIM

The ornamental design for a medical holeplate, as shown and described.

DESCRIPTION

FIG. 1 is a perspective view of a medical holeplate showing my new design;

FIG. 2 is a perspective view from the opposite end thereof and showing the opposite side thereof;

FIG. 3 is a side elevational view thereof;

FIG. 4 is a bottom plan view thereof;

FIG. 5 is an end view thereof taken from the left end of FIG. 1; and

FIG. 6 is an end view thereof taken from the left end of FIG. 2.
